RADIO CABINET

Melvin H. Boldt, Glenview, Ill., assignor to Zenith Radio Corporation, a corporation of Delaware

Filed Sept. 21, 1960, Ser. No. 62,232

Term of patent 14 years

(Cl. D56—4)

Fig. 1

Fig. 2

Fig. 3

FIGURE 1 is a perspective view of a radio cabinet showing my new design;

FIGURE 2 is a front elevational view under a different ambient lighting condition; and

FIGURE 3 is another front elevational view under a still different ambient lighting condition.

The novel features of my design reside in the provision of a multi-apertured semi-bright or satin finish panel having a circularly brushed surface effect to present multitudinous varying reflection and moire effects dependent upon ambient lighting and the viewing aspect of the observer, as exemplified by comparison of the several figures of the drawing.

The placement and configuration of the radio control knobs, the indicia appearing thereon, and the crown and shield emblem on the front panel are illustrative only and are not considered to be essential components of my novel design.

The side not shown is the same as the side shown and the top, bottom and back are plain and unornamental.

I claim:

The ornamental design for a radio cabinet, substantially as shown and described.
